Primary Examiner — Jack Reickel*Assistant Examiner* — Bobby W Jones II(74) *Attorney, Agent, or Firm* — John P. McGonagle(57) **CLAIM**

The ornamental design for a ductwork patch, as shown and described.

DESCRIPTION

FIG. 1 is a perspective view of a ductwork patch showing my new design;

FIG. 2 is front view thereof;

FIG. 3 is a rear view thereof;

FIG. 4 is a top view thereof, the opposite side being a mirror image thereof.

The broken line showing of ductwork in FIG. 1 is for the purpose of illustrating environmental structure and forms no part of the claimed design.
